UNITED STATES PATENT OFFICE.

WILLIAM ALENIUS, OF ROCK SPRINGS, WYOMING.

RETORT.

Application filed May 20, 1921. Serial No. 471,084.

To all whom it may concern:

Be it known that I, WILLIAM ALENIUS, residing at Rock Springs, county of Sweetwater, and State of Wyoming, a citizen of the United States, have invented certain new and useful Improvements in Retorts, of which the following is a specification.

This invention relates to the volatilization of vapors and oils from oil shale and sand, and it consists in an improved apparatus or retort for collecting the vapors and gases arising from the oil shale and sand being treated, and drawing them off through pipes by suction, and finally condensing the vapors and gases into oil.

A further object of the invention is to effect a complete agitation of the oil shale and sand while being treated to effect a more complete separation.

20 In the accompanying drawings:

Fig. 1 is a top plan view of the device;

Fig. 2 is a longitudinal vertical section thereof;

25 Fig. 3 is a transverse section on line 3—3 of Fig. 1;

Fig. 4 is an enlarged detail view of the rotary agitator or conveyor.

The numeral 1 indicates a stationary hollow cylinder, or hollow cylindrical drum, 30 having arranged therebeneath a plurality of fire-boxes 2, 3, 4 and 5. Arranged at the forward end in the roof of the hollow cylindrical drum or retort is a feed-hopper 6 provided with a plurality of slide-valves

35 7, 7. At rear of the drum, and on the lower side thereof is an outlet 8 provided with a plurality of regulating-valves 9, 9. The numeral 10 indicates a shaft rotatably mounted longitudinally of the drum or retort 1.

40 Mounted along the shaft at intervals are a plurality of spaced cross-arms 11 acting to convey the oil shale and sand longitudinally of the drum, the material being raised from the bottom of the drum by the spirally-arranged buckets or conveyors consisting preferably of corrugated angle-irons 12, thereby keeping the material stirred up as it is conveyed along the drum, causing the gases to rise from the heated material.

45 50 To retard more or less the progress of the material passing through the drum, I preferably provide a plurality of stops 13 placed at intervals along the spiral angle-irons 12, in such way as to form buckets or

55 compartments under the angle-irons. In this manner, the material is raised from the

bottom of the drum nearly to the top thereof, falling back again to the bottom of the drum where it is again picked up and re-agitated as distributed.

To further retard the progress of the material, reverse L-shaped angle-irons 14 are placed diagonally between the spiral angle-irons 12, which are in reverse direction thereto. These likewise tend to lessen the progress of the material as it travels longitudinally of the cylindrical drum or retort. A gear-wheel 15 keyed to the shaft 10 at the outer end thereof serves as a means of rotation.

70 As stated, by agitating the heated material in this manner, gases arise therefrom, and to arrest these gases I arrange a dome or chamber 16 at the top of the drum and longitudinally thereof, in which the gases accumulate.

75 Leading from the dome 16 are a plurality of pipes 17 connected to a delivery pipe 18, which in turn is connected by a pipe 19 to a suction fan 20, by which the gases are drawn from the dome 16. From the suction fan the gases pass through the pipe 21 leading to a series of condensing-coils 22 located in a cooling-tank 23 where the gases are condensed into oil, and pass from the coils to a collecting-tank 24.

80 85 Connected to the oil tank 24 by a pipe 25 is a water-cooler 26, which in turn is connected by pipe 27 to container 28, where the dry gases are collected.

90 The operation is as follows:—The oil shale and sand is emptied into the hopper 6 where it is deposited in the cylindrical drum or retort, which, as described, is heated by the plurality of furnaces therebeneath. 95 The rotary conveyor being in operation picks up the sand from the bottom of the drum, and owing to the spiral construction of the buckets or conveyors thereon, the material is caused to travel longitudinally of the retort and upwardly along the side walls thereof until these buckets reach such an angle that the material is ejected therefrom, falling back to the bottom of the drum where it is again picked up by the following buckets, carried still further, and so on till it finally reaches the rear or outer end of the drum where it is ejected through the outlet 8 leading from the drum to a suitable receptacle.

100 105 110 The gases arising from the agitation of the heated material collect in the dome 16.

from which they are carried off by the suction fans 7 to the condensing coils 22, which act to reduce the vaporous gases to a liquid, which are then collected into the chamber 24.

It will thus be seen that I have arranged a simple and expedient device for carrying out the purpose, one which is simple in construction and efficient in operation.

10 I claim:

1. A device for extracting oil from oil shale and sand comprising a cylindrical retort, heating means arranged beneath said retort, an inlet and outlet for said retort, a 15 rotary agitator and conveyor arranged longitudinally of the retort, comprising a shaft journaled at its outer end in said retort, a plurality of spaced cross-arms keyed to said shaft, spiral buckets or conveyors wound circumferentially of said cross-arms, said spiral conveyor consisting of L-shaped 20 angle-irons wound spirally of the shaft and received in the outer ends of the cross-arms, said conveyor being of a diameter equal to the inner circumference of the retort and perpendicular stops at spaced intervals on 25 said angle-irons, the inner circumference of the retort and perpendicular stops at spaced intervals on said angle-irons and means for collecting

the gases arising from the agitated material.

2. A device for extracting oil from oil shale and sand comprising a cylindrical retort, heating means arranged beneath said retort, an inlet and outlet for said retort, a rotary agitator and conveyor arranged longitudinally of the retort, comprising a shaft 30 journaled at its outer end in said retort, a plurality of spaced cross-arms keyed to said shaft, spiral buckets or conveyors wound circumferentially of said cross-arms, said spiral conveyor consisting of L-shaped 35 angle-irons wound spirally of the shaft and received in the outer ends of the cross-arms, said conveyor being of a diameter equal to the inner circumference of the retort and perpendicular stops at spaced intervals on 40 said angle-irons, a dome at the top of said retort comprising a longitudinal pocket to collect the gases arising from the agitated material, and means for carrying gases from 45 said retort and condensing the gases into oil. 50

In testimony whereof I hereunto affix my signature.

WILLIAM ALENIUS.
